UNITED STATES PATENT OFFICE

ELsie F. MILLER, OF NEW YORK, N. Y.

HAND BAG

Application filed May 12, 1930. Serial No. 451,811.

This invention relates generally to hand bags and more particularly to a foldable combination hand bag for use as a kit or ensemble for practical purposes but which also embodies the aesthetic advantages always desirable in ladies' hand bags and similar articles.

The primary object of the invention is to provide a hand bag or the like particularly adapted for use as a kit or ensemble for carrying such articles as a raincoat, sandals, hat covering, and the like, all of which, together with the hand bag itself are desirably made of water-proof material, the hand bag also being adapted to contain various other accessories usually carried by ladies.

Another object of the invention is to provide a ladies' hand bag which is adapted to contain a raincoat, sandals, hat cover and the like in such fashion that the external appearance of the hand bag gives no indication of such contents, but, rather presents the appearance of an artistic type of hand bag.

Still another object of the invention is to provide a foldable hand bag of substantially square form when opened for insertion or removal of the contents, but which may also be made in other shapes, the arrangement being such that the opening through which the contents are inserted or removed being normally concealed within the folded side portions of the hand bag, thus securely and compactly holding the articles therein and yet rendering the hand bag easy to open and close, convenient and practical in its use and neat in its appearance.

Yet another object is to simplify and improve the construction of hand bags suitable for practical purposes as stated above, and to render the same economical in cost of manufacture as well as efficient and durable.

Other objects and advantages of the invention will be hereinafter specifically pointed out, or will become apparent, as the specification proceeds.

With the above indicated objects in view, the invention resides in certain novel constructions and combinations and arrange-

ment of parts, clearly described in the following specification and fully illustrated in the accompanying drawings, which latter show embodiments of the inventions as at present preferred.

55 In said drawings:

Fig. 1 is a side elevation of the hand bag as it appears when carried by the user;

Fig. 2 is a side elevation of the hand bag opposite to that shown in Fig. 1;

Fig. 3 is an end elevation;

Fig. 4 is a transverse sectional view taken on the line 4—4 of Fig. 1 looking in the direction of the arrows;

Fig. 5 is a top plan view of the exterior 65 of the bag when opened; and

Fig. 6 is an interior plan view of the hand bag when in position to insert or remove the contents.

As shown in the drawings the hand bag 70 includes a foundation construction of relatively stiff material, such as fibre board, cardboard, leather, or the like and formed in three sections, including a median section 10 and opposite side sections 11 and 12, the sections 11 and 12 being foldable along the lines 13 and 14 which define the section 10. The outer sides of the sections 10, 11 and 12 are preferably covered with a suitable water-proof material 15, which may be rubber, 75 water-proof silk, or other rubberized or water-proof fabric. The outer covering 15 may also be made of leather or any other desired material not entirely water-proof in itself whenever desired, and whatever material is employed, any desirable decorative or figured appearance may be applied thereto to impart an aesthetic appearance to the exterior of the hand bag.

Similarly a suitable water-proof covering, 80 of rubber, rubberized fabric, or other material is preferably applied to the interior of the sections 10, 11 and 12 as indicated at 16; the outer and inner coverings 15 and 16 being preferably stitched to the outer edges of the sections 11 and 12 as indicated at 17, and also at the sides of the median section 10 as indicated at 18. As seen in Figs. 3, 4 and 6 the interior of the side members 11 85 and 12 is formed to provide a flexible com-

partment 19 including intercommunicating receptacle or pocket portions 20 and 21 respectively, these pocket portions including enclosing portions 22 and 23 having substantially right angular wall portions 24 and 25, which extend around the side edges of the sections 11 and 12 respectively and meet at the opposite ends of the median section 10. These pocket portions 20 and 21 are preferably, also, formed of any suitable waterproof or water-resisting material. The angular wall portions 24 and 25 may be reinforced with suitable stiffening material and this stiffening material, may extend exactly around the sides of the pocket portions 20 and 21 in the form of a stiffening rim, as indicated at 39. Suitable means are provided to enclose the compartment 19, and for this purpose, in this instance, I provide a series of snap fasteners 26 along the meeting edges 27 and 28. Other types of fastening devices, such as a so called hookless or talon fastener may be employed instead of the snap fasteners 26.

To close the present hand bag, the opposite sides are folded one against the other so that the pocket portions 22 and 23 abut against each other as shown in Figs. 1 and 4 inclusive; and means are provided to secure the side sections 11 and 12 together, as, for instance, a pair of straps 29 and 30 provided at opposite points or edges of the side section 11, these straps, in the present showing, being adapted to cooperate with snap fasteners 31 and 32 provided on the outer side of the section 12. Other means may be employed to secure the folded sections together, as, for instance, a hookless or talon fastener extending around the meeting outer sides of the angular portions 24 and 25.

When closed as described the hand bag may be conveniently carried by means of a handle 33 provided at the exterior of the median section 10.

As already stated, a primary advantage of the present construction is the convenient arrangement for carrying articles particularly useful for protection against the weather, such as a raincoat, rubbers or rubber sandals, hat protector, and the like. In the embodiment shown, the raincoat 34 is folded up to substantially the same shape as the hand bag when opened as shown in Figs. 5 and 6. The raincoat 34 is then inserted within the compartment 19 through the opening 34; and when thus inserted, the raincoat which is preferably of rather light weight, such as thin rubberized fabric, so that it may be folded up into a flat package, constitutes a bottom for the compartment 19. Other articles such as light weight rubbers or sandals 35 and a hat protector 36, may then be inserted over the raincoat within opposite sides of the compartment 19. The compartment is then closed by means of the fasteners 26, and the

sections folded one against the other along a line parallel with the opening 34, and secured by means of the straps 29 and 30.

One important advantage of the present construction is that the hand bag is specially adapted for use as a combination "rainy day ensemble", being adapted to compactly and efficiently carry the articles needed in case of rain as well as other articles, and rendering it unnecessary for the user to carry an umbrella. Also, the present hand bag meets all the necessary purposes of the conventional type of hand bag, since the various small articles usually needed may be carried in a supplementary pocket 37 provided above one of the pocket portions 20 or 21; and a small supplementary pocket for change and the like may also be provided at the exterior of one of the sections 11 or 12, as indicated at 38.

As stated hereinabove, the angular wall portions 24 and 25 and the marginal edges of the pocket portions 20 and 21 may have a foundation of stiffening material 39. Also, if desired, the entire top of one of the pocket portions 20 or 21 may have a stiffening foundation; or, both pocket tops may be made relatively inflexible.

While I have shown the present hand bag as of substantially square form when opened, so as to produce a hand bag of triangular form when closed, the hand bag is equally adaptable to construction in a variety of other shapes.

The hereinbefore described construction admits of considerable modification without departing from the invention; therefore, it is the wish not to be limited to the precise arrangements shown and described, which are as aforesaid, by way of illustration merely. In other words the scope of protection contemplated is to be taken solely from the appended claims, interpreted as broadly as is consistent with the prior art.

What is claimed is:

1. A hand bag comprising a body of substantial marginally square formation having diagonally arranged spaced parallel crease lines reaching diagonally opposed corners to provide a relatively stiff intermediate back portion and matched substantially triangular-shaped stiff side portions upon folding of the body, pockets carried by the side portions at their inner faces and having mouth openings confronting each other and the intermediate back portion, the pockets at their mouth openings being adapted to overlap throughout, and fasteners at the overlap to close the same.

2. A hand bag comprising a body of substantial marginally square formation having diagonally arranged spaced parallel crease lines reaching diagonally opposed corners to provide a relatively stiff intermediate back portion and matched substantially triangular-shaped stiff side portions upon folding of

the body, pockets carried by the side portions at their inner faces and having mouth openings confronting each other and the intermediate back portion, the pockets at their mouth 5 openings being adapted to overlap throughout, fasteners at the overlap to close the same, and straps carried by one side portion and detachably engageable with the other side portion to hold the body folded.

10 In testimony whereof I hereby affix my signature.

ELsie F. MILLER.
